[57] CLAIM

The ornamental design for a combination knife and pipe tamper, as shown and described.

DESCRIPTION

FIG. 1 is an elevational view of a combination knife and pipe tamper showing my new design;

FIG. 2 is a bottom plan view thereof;

FIG. 3 is a cross sectional view, taken along line 3—3 of FIG. 2;

FIG. 4 is a cross sectional view, taken along line 4—4 of FIG. 1;

FIG. 5 is a cross sectional view, taken along line 5—5 of FIG. 1;

FIG. 6 is a top plan view thereof;

FIG. 7 is an elevational view, with the knife blade exposed; and

FIG. 8 is a cross sectional view, taken along line 8—8 of FIG. 7.
